COMBINATION BABY BOTTLE AND TOY

Carl M. Bloomberg, 4 Holly Drive,
East Northport, N.Y. 11731

Filed Mar. 7, 1968, Ser. No. 10,883

Term of patent 14 years

(Cl. D83—8)

FIG. 1 is a perspective view of a combination baby bottle and toy;

FIG. 2 is an elevational view thereof;

FIG. 3 is an elevational view of the bottle turned 90° from the view shown in FIG. 2;

FIG. 4 is a top plan view; and

FIG. 5 is a bottom plan view thereof.

I claim:

The ornamental design for a combination baby bottle and toy, substantially as shown.
